MACHINE FOR REMOVING THE BUTT-ENDS OF EARS OF CORN.

13,206.

Specification of Reissued Letters Patent. Reissued Feb. 14, 1911.

Original No. 907,849, dated December 29, 1908, Serial No. 417,312. Application for reissue filed December 28, 1909. Serial No. 535,376.

DIVISION A.

To all whom it may concern:

Be it known that we, SAMUEL E. MORRAL and WILLIAM W. MORRAL, citizens of the United States, residing at Morral, in the county of Marion and State of Ohio, have invented certain new and useful Improvements in Machines for Removing the Butt-Ends of Ears of Corn, of which the following is a specification.

This invention relates to machines for removing the butt-ends-of ears of corn and is designed more particularly for operating upon green corn, such as is used in canning factories.

The present invention is in the nature of an improvement upon Patent No. 801,258, granted to us October 10, 1905, and the object of the same is to provide a machine of this character with a high degree of efficiency, both as to the character of the work done and as to the speed with which the ears of corn are handled.

To this end it is a further object of the invention to provide a machine of this character with a support to maintain an ear of corn in a substantially horizontal position, a guide to properly position the ear relatively to the butt-removing device, positively operated means for holding the ear in engagement with the guide, and means for moving the ear along the guide toward the butt-removing device.

With these objects in view our invention consists in certain novel features and in certain combinations and arrangements of parts hereinafter to be described, and then more particularly pointed out in the claims.

In the accompanying drawings, Figure 1 is a top plan view of a machine embodying our invention; Fig. 2 is an end elevation of the same; Fig. 3 is a side elevation thereof; Fig. 4 is an elevation of the side opposite that shown in Fig. 3; Fig. 5 is a detail sectional view of the cutting mechanism, together with the gaging and holding rollers; Fig. 6 is an elevation of a portion of the machine, showing a modified form of gaging and holding rollers with additional means for conveying ears of corn longitudinally thereof; Fig. 7 is an end elevation of what is shown in Fig. 6; Fig. 8 is a detail view of a modified form of gaging rollers; Figs. 9 and 10 are end views of the gaging rollers

shown in Fig. 8; and Fig. 11 is a detail view showing a modified form of the guide.

In Figs. 1 to 5 of these drawings we have illustrated one embodiment of our invention and have shown the same as comprising a main frame 1, preferably substantially rectangular in shape and mounted upon suitable standards or supports 2. A drive shaft 3 extends longitudinally of this frame and is mounted in suitable bearings 4 carried by brackets 5 which are secured to the side of the frame 1. This shaft may be rotated by any suitable means and is here shown as provided with a driving pulley 6 on the outer end thereof. A second shaft 7 extends transversely of the frame 1 and is mounted in suitable bearings 8 carried on the opposite sides of said frame. This shaft is provided on the end adjacent to the shaft 3 with a beveled pinion 9 adapted to mesh with a similar pinion 10 carried by said shaft 3.

Mounted in the main frame 1 and extending transversely thereof are suitable guides, such as gaging rollers, having their adjacent sides spaced apart a distance sufficient to admit the stem or tapered portion of the butt-end of the ear of corn, but not sufficient to permit the passage of the ear of corn, thus limiting the longitudinal movement of the ear of corn and causing the same to be presented to the cutter in the proper position. In the form here shown, these gaging rollers comprise a pair of parallel shafts 11 and 12 arranged in substantially the same vertical plane, journaled in one of the side members of the main frame 90 and extending inwardly therefrom to a point near the opposite side member.

Mounted on or secured to the shafts 11 and 12 are suitable feed screws 13 and 14 having right and left hand threads, respectively, adapted to be rotated in opposite directions, whereby those portions of the threads on the adjacent sides of the two gaging rollers move in the same direction and tend to carry the ear of corn, the end 100 of which is in engagement therewith, longitudinally of said rollers.

The gaging rollers may be rotated in opposite directions in any suitable manner, but we have here shown the shafts 11 and 12 as extending for some distance beyond

the outer side of the main frame 1 and having their outer ends supported in suitable bearings 15 and 16 formed in a bracket 17 secured to the side of the main frame 1. 5 The upper shaft 11 is here shown as rotated by a sprocket chain 18 which extends about a sprocket wheel 19, secured to the outer end of the shaft 11, and a similar sprocket wheel 20 secured to the corresponding end 10 of the shaft 7. A pinion 21 mounted on the shaft 11 meshes with a corresponding pinion 22 carried by the shaft 12 and serves to rotate the shaft 12 at a uniform speed with the shaft 11, but in the opposite direction.

A suitable butt-removing device is mounted near the free or discharge ends of the gaging rollers and is adapted to engage the ears of corn as the same are fed longitudinally of said gaging rollers and remove the butt-ends thereof. This device is here shown as comprising a rotary disk 23, which is rigidly secured to one end of a shaft 24 which is journaled in suitable bearings 25 secured to the side member of the frame 1 and provided near the end opposite that to which the cutting disk 23 is secured with a worm wheel 26 adapted to mesh with a worm 27 secured to the shaft 30, whereby a rotary movement is imparted to the disk 23. Suitable shearer bars 28 and 29 are supported from the side member of the frame 1 beneath the cutter disk 23 and cooperate therewith. These shearer bars, 35 which are, preferably two in number, are supported on opposite sides of the cutter disk and support both the body and the butt of the ear during the cutting operation, thereby enabling the cutter to make a clean 40 smooth cut. The cutter disk 23 preferably extends some distance beyond the free or discharge end of the gaging rollers, whereby the ear of corn is engaged and the butt severed therefrom before the ear has passed 45 the end of the gaging rollers. Suitable means are provided for supporting an ear of corn in a position to engage said guide and to be operated upon by said cutter, for holding said ear of corn in engagement with 50 said guides, and for feeding said ear of corn along said guides toward said cutter.

In the present machine the supporting means and the holding means comprise a plurality of rollers, the lower roller, or 55 rollers, serving as a support for the ear and the upper roller acting to hold the ear against the guides while it is being moved toward the butt-removing device by suitable feeding devices. The lower or supporting 60 roller or rollers are, as here shown, positively rotated and assist in holding the ear against the guides, but this is not necessary to the successful operation of the machine, as the upper or holding roller co-operating 65 with a support of any kind will hold the

ear against the guides while it is being moved along the guides by any suitable means.

In that form of the machine shown in Figs. 1 to 5, the supporting and holding rollers are provided with feeding means to move the ear along the guides and, therefore, the holding and supporting rollers also constitute feeding rollers which engage the ear between them, move it along the guide and hold it against the guide. To this end, these rollers comprise a pair of parallel shafts 30 and 31 journaled at their opposite ends in the side members of the frame 1 and lying in substantially the same horizontal plane, which horizontal plane is slightly lower than that in which the shaft 12 of the lower gaging roller is located. Formed on or secured to the shafts 30 and 31 are rollers provided with feed screws 85 having their threads turned in the same direction and in a direction corresponding to that of the lower gaging roller 14. These rollers and their screws form feeding rollers 32 and 33. A vertically movable feeding roller 34 is mounted above the feeding rollers 32 and 33 and preferably in a vertical plane lying between the vertical planes of the axes of said feeding rollers. This feeding roller preferably comprises a shaft 35 90 journaled in bearings 36 and 37 formed in the ends of arms 38 and 39, which are pivotally supported on the main frame, the arm 38 being mounted on a suitable stud shaft or pivot pin 40 secured to the side of the main frame 1, and the arm 39 being journaled on the shaft 11 of the upper gaging roller 13. The feed roller proper is mounted on or secured to the shaft 35 between the bearings 36 and 37 and consists of a roller provided with a screw having its thread turned in a direction opposite to that in which the threads of the lower rollers 32 and 33 are turned and corresponding to the direction in which the thread of the upper gaging roller 13 is turned. We also prefer to provide suitable means for holding the upper roller 34 in its proper position. These means are here shown as comprising rods 41 105 extending through suitable guides 42 carried by the main frame and secured at one end to upwardly extending lugs or arms 43 carried by the arms 38 and 39. A spring 44 is coiled about that end of each rod 41 lying beyond the apertured lug 42 and is confined between said apertured lug and a suitable stop on the outer end of the rod, such as a thumb nut 45. The tension of these springs is such as to counterbalance the upper feeding roller 34 and permit the same to engage the ears of corn without exerting too great a pressure thereon. The rollers may be rotated in any suitable manner.

In the present instance we have shown 130

the shafts 30 and 31 of the rollers 32 and 33 as provided with gears 46 and 47, the gear 46 being actuated from the gear 22 on the shaft 12 by means of an intermediate gear 48, while the gear 47 is actuated from the gear 46 by means of an intermediate gear 49, the relation of the several gears being such as to cause the lower rollers 32 and 33 and the lower gaging roller 14 to be rotated in the same direction at a uniform rate of speed. The upper feeding roller 34 is preferably rotated by means of a sprocket chain 50 extending about a sprocket wheel 51 secured to the shaft 35 and a similar sprocket wheel 52 secured to the shaft 11 of the upper gaging roller 13, thus causing the upper feeding roller 34 and the upper gaging roller 13 to be rotated in the same direction and at a uniform rate of speed.

20 A feed trough 53 extends at substantially right angles to the feeding rollers and is supported in a substantially horizontal position by means of a brace 54. A suitable conveyer belt extends longitudinally of the trough 53 and, as here shown, comprises a sprocket chain 55 extending about a sprocket wheel 56 located at one end of the trough 53 and mounted on a shaft 57 which is journaled in suitable bearings 58 secured to the main frame. At the opposite end of the trough 53 the sprocket chain 55 extends about a similar sprocket wheel 59 mounted on a suitable shaft 60 carried by a bracket 61, which is supported on the outer end of the trough 53. The shaft 57 preferably extends beyond the sprocket wheel 56 and is adapted to be rotated by means of a sprocket chain 62 extending about a sprocket wheel 63, secured to the outer end 40 of said shaft and about a sprocket wheel 64 mounted on the outer end of the shaft 31 of one of the feeding rollers. A short corrugated feeding roller 65 extends transversely of the trough 53 near the inner end thereof and is capable of vertical movement, whereby the same is adapted to rest upon the ears of corn as they are fed longitudinally of the trough 53 by the feed belt and to accommodate itself to ears of corn of different sizes. The corrugated feed roller 65 is preferably mounted upon a shaft 66 journaled in a bearing 67 formed in the outer end of an arm 68, the opposite end of which is journaled upon the shaft 35 of the vertically movable feeding roller 34. A stop or bracket 68^a, mounted on the trough 53, extends upwardly to a point beneath the arm 68 and is adapted to engage said arm to limit its downward movement. The shaft 66 also receives its rotary movement from the shaft 36 by means of a sprocket chain 69 extending about similar sprocket wheels 70 and 71 mounted on the shafts 66 and 35, respectively.

65 In the operation of the machine as thus

described, the ears of corn are placed in the feed trough 53 with their butt-ends foremost, and, as they are carried inwardly by the feeding belt 55, they are engaged by the corrugated feed roller 65 and forced between the lower feeding rollers 32 and 33 and the vertically movable upper roller 34, the direction of rotation of these rollers being such as to move the ear of corn transversely thereof and longitudinally of the frame 1 until the butt-end thereof comes into engagement with the gaging rollers 13 and 14, the feeding rollers 32 and 33 being located in a slightly lower plane than the lower gaging roller 14, thus permitting the stem or tapered portion of the butt to extend between the two gaging rollers. As stated, the gaging rollers 13 and 14 are spaced apart a distance sufficient to permit the stem or small end of the butt of the ear 85 or corn to enter between the same, but the space between the rollers is not sufficient to permit the ear of corn itself to enter, and, as these rollers have no vertical movement, they form an efficient stop to prevent the further movement of the ear of corn in a direction transversely of the length of the several rollers. The feed screws on the feeding rollers serve to convey the ear of corn longitudinally thereof while it is being held in engagement with the gaging rollers, and the feeding screws on the gaging rollers, which are rotated in the same direction as the feeding rollers, facilitate this longitudinal movement of the ear of corn. As the ear approaches the discharge end of the roller it comes into engagement with the cutter 23, which is so located relatively to the gaging rollers as to engage the ear at such a point as to sever the stem and butt-end of the ear of corn, thereby removing the butt-end of the ear and loosening the husks on the ear so that the same are readily removed by the husking machine to which the ear of corn is fed after it leaves the machine 100 for cutting off the butt-end thereof. As the butt-end of the ear of corn is severed, it is discharged from the gaging rollers and drops downwardly through the frame where it may be disposed of in any suitable manner, the ear of corn itself being carried to the discharge end of the feeding rollers, where it is dropped upon a suitable table 72 provided with a downwardly inclined portion 73 which serves to discharge the ear of corn into a suitable receptacle or conveyer.

105 While we have shown and above described the gaging rollers and the supporting and holding rollers as being provided with feed screws, it is obvious that a smooth roller may be employed for this purpose if suitable means are provided for feeding the ear longitudinally thereof, and, in Figs. 6 and 7 of the drawings, we have shown a mechanism adapted to accomplish this result. In 110

these figures we have shown gaging rollers 74 and 75 as comprising smooth rollers adapted to be rotated in the same manner as the rollers 13 and 14 are rotated and having the cutter 23 and shearers 28 and 29 located in the same relation thereto. The holding and supporting rollers comprise two smooth rollers 76 and 77, located one above the other in a substantially vertical plane and adapted to receive the ear of corn from the feed trough and to hold the same with its butt-end in engagement with the gaging rollers 74 and 75. A suitable conveyer is provided for moving the ears of corn longitudinally between the supporting and holding rollers, along the guides and into engagement with the cutter. This conveyer preferably comprises a pair of endless belts 78 located on opposite sides of the rollers 76 and 77 and provided with fingers or plates 79 adapted to engage the ears of corn on the opposite sides of the centers of said rollers and feed the same forward. These belts are preferably mounted on suitable drums 80 and 81, mounted on shafts 82 and 83, respectively, at opposite ends of the rollers, which shafts may be operated from the driving mechanism of the machine in any suitable manner. The construction and operation of the modified form of the machine, with the exception of the changes above described, are the same as that of the machine first described, with the exception that the corn is fed directly to the conveyer 78 and the feed trough 53 dispensed with.

It will further be apparent that various means may be employed for removing the butt-ends of the ears, and, in Figs. 8 to 10 of the drawings, we have illustrated another form of device for accomplishing this. As shown in those figures, the gaging rollers 13 and 14 are provided at their outer edges with snapping rollers, which, in the present instance, are corrugated rollers 84 eccentrically mounted on the ends of the gaging rollers and so arranged relatively to the spiral groove in said gaging rollers as to receive the end of the ear between the same when it is discharged from the gaging rollers, the continued revolution of the gaging rollers and the snapping rollers serving to pinch or snap off the butt-end of the ear. When the snapping rollers or similar devices are employed, the cutting mechanism 23 is dispensed with. Further, it will be apparent that the machine can be successfully operated without the use of gaging rollers, as it is possible to substitute some other form of guide therefor. In Fig. 11 of the drawings, we have shown one form of guide with which the machine will successfully operate. This guide is shown in connection with the smooth rollers shown in Figs. 6 and 7 and comprises two fixed guides 85 and 86 mounted in substantially the same positions as

were occupied by the gaging rollers 74 and 75. These guides are, however, stationary and are here shown in the form of metal plates extending parallel with the rollers 76 and 77 and having their adjacent edges spaced some distance apart and preferably rounded or bent in such a manner as to cause the same to diverge toward the feeding rollers. These guides receive the end or butt of the ear between them and serve to limit the movement thereof transversely of the rollers and to guide the ear into a proper cutting position relatively to the cutter disk 23 as the ear is moved longitudinally of the feeding rollers by means of the conveyer 78.

From the foregoing description it will be apparent that we have provided a machine of the character described, in which the ears of corn may be fed to the same horizontally, will be moved into proper position relatively to the cutter and will be positively held in that position and positively fed to the cutter, the construction and operation of the machine being such that the work is accurately performed, a uniform portion of the butt-end of each ear of corn being cut away; and further, that the machine is capable of being operated at a high rate of speed and the ears of corn fed to the same in rapid succession, thus providing a machine having a high degree of efficiency both in the character of the work performed and in the speed with which the ears of corn are handled.

It will further be apparent that our machine, in its essential characteristics, comprises a butt-removing device, a guide leading to said butt-removing device, a support for an ear of corn, means for holding said ear of corn against said guide, and means for feeding the ear of corn along said guide. These features of construction are capable of wide modification and we have, therefore, shown each feature in two or more forms to indicate a few of the lines along which these modifications can be made. In the drawings, the butt-removing device is shown both as a rotary cutter and as a pair of snapping rollers; the guide is shown as a pair of spirally ribbed rollers, as a pair of smooth rollers and as a pair of fixed bars; the holding and supporting rollers are shown in different arrangements; and the feeding means is shown as comprising spiral ribs carried by the holding and supporting rollers and also as an endless belt having fingers to engage the ears of corn. In each instance the feeding means is of such a character as to feed the ear positively along the guide and to hold the same in proper relation to the butt-removing device. The modifications can, of course, be carried much further and we, therefore, wish it to be understood, that we do not desire to be limited to the details of construction shown and described, for obvious

ous modifications will occur to a person skilled in the art.

Having thus fully described our invention, what we claim as new and desire to secure by Letters Patent, is:—

1. In a machine of the character described, the combination, with gaging rollers, and a cutter operatively supported near the discharge end thereof, of positively operated means for holding an ear of corn against said gaging rollers.

2. In a machine of the character described, the combination, with gaging rollers, and a cutter operatively supported near the discharge end thereof, of positively operated means for holding an ear of corn against said gaging rollers and for conveying said ear of corn along said gaging rollers into engagement with said cutter.

3. In a machine of the character described, the combination, with gaging rollers, and a cutter operatively supported near the discharge end thereof, of positively operated means for holding an ear of corn against said gaging rollers, and means for conveying said ear of corn along said gaging rollers and into engagement with said cutter.

4. In a machine of the character described, the combination, with gaging rollers, and a cutter operatively supported near one end thereof, of a roller for holding an ear of corn against said gaging rollers.

5. In a machine of the character described, the combination, with gaging rollers, and a cutter operatively supported near the discharge end thereof, of rollers for holding an ear of corn against said gaging rollers, and means for conveying said ear of corn along said gaging rollers and into engagement with said cutter.

6. In a machine of the character described, the combination, with gaging rollers comprising a pair of oppositely rotating rollers mounted one above the other, and a cutter operatively supported near the discharge end of said rollers, of rollers mounted at one side of said gaging rollers and adapted to hold an ear of corn against the same, and means for conveying an ear of corn longitudinally of said rollers.

7. In a machine of the character described, the combination, with gaging rollers, and a cutter operatively mounted near the discharge end thereof, of rollers for holding an ear of corn against said gaging rollers and comprising a plurality of rollers, one of which rollers is movable relatively to another of said rollers.

8. In a machine of the character described, the combination, with gaging rollers, and a cutter operatively mounted near the discharge end thereof, of rollers for holding an ear of corn against said gaging rollers and comprising a plurality of rollers, one of which rollers is movable relatively to another

of said rollers, and means for feeding said ear of corn longitudinally to said gaging rollers.

9. In a machine of the character described, the combination, with gaging rollers, and a cutter operatively supported near the discharge end thereof, of rollers extending substantially parallel to said gaging rollers and adapted to hold an ear of corn in engagement with said gaging rollers, means for feeding said ear of corn longitudinally of said rollers, a feed trough extending at substantially right angles to said feeding rollers, and means for conveying an ear of corn longitudinally of said trough and into engagement with said feeding rollers.

10. In a machine of the character described, the combination, with gaging rollers, and a cutter operatively supported near the discharge end thereof, of rollers extending substantially parallel to said gaging rollers and adapted to hold an ear of corn in engagement with said gaging rollers, means for feeding said ear of corn longitudinally of said rollers, a feed trough extending at substantially right angles to said feeding rollers, a conveyer moving longitudinally of said trough, and a positively rotated roller mounted above said feed trough and adapted to engage the ears of corn and move the same into engagement with said feeding rollers.

11. A machine of the character described comprising a support, a guide, a butt-removing device arranged near said guide, means for positively holding an ear of corn against said guide and for moving the same along said guide and into engagement with said butt-removing device.

12. A machine of the character described comprising a support, a guide, a butt-removing device arranged near said guide, means for positively holding an ear of corn against said guide, and other means for moving an ear of corn along said guide and into engagement with said butt-removing device.

13. A machine of the character described comprising a support, a guide, a butt-removing device arranged near said guide, positively operated means arranged above said support to hold an ear of corn against said guide, and means for moving said ear of corn along said guide and into engagement with said butt-removing device.

14. A machine of the character described comprising a support, a guide, a butt-removing device arranged near said guide, a roller arranged above said support and in a position to engage an ear of corn, means for rotating said roller to cause it to hold an ear of corn against said guide, and means for moving said ear of corn along said guide and into engagement with said butt-removing device.

15. A machine of the character described

- comprising a guide, a butt-removing device arranged near said guide, means for conveying an ear of corn along said guide toward said butt-removing device and for holding the same at a proper angle thereto, and means located above said conveying means for holding an ear of corn against said guide.
16. A machine of the character described comprising a support, a guide, a butt-removing device arranged near said guide, means located above said support to hold an ear of corn against said guide, and means for positively moving an ear of corn along said guide and into engagement with said butt-removing device.
17. A machine of the character described comprising a guide, a butt-removing device near the discharge end of said guide, a holding device comprising a roller and a part cooperating therewith to hold an ear of corn against said guide, and means for conveying an ear of corn longitudinally to said guide.
18. A machine of the character described comprising gaging rollers, butt-removing means near the discharge end thereof, means for holding an ear of corn against said gaging rollers, and means for conveying said ear of corn longitudinally thereof.
19. A machine of the character described comprising gaging rollers, butt-removing means near the discharge end thereof, rollers for holding an ear of corn against said gaging rollers, and means for feeding the same longitudinally to said rollers.
20. A machine of the character described comprising a guide, a cutter operatively supported near the discharge end thereof, a roller for holding an ear of corn against said guide, means for conveying said ear of corn longitudinally thereof and shearer bars supported near the lower edge of said cutter and on opposite sides thereof.
21. In a machine of the character described, the combination, with gaging rollers, and butt-removing means supported near said rollers, of means for holding an ear of corn in engagement with said gaging rollers.
22. In a machine of the character described, the combination, with gaging rollers, and butt-removing means supported near the discharge end of said rollers, of means for holding an ear of corn against said gaging rollers and for conveying said ear of corn along the same into engagement with said butt-removing means.
23. In a machine of the character described, the combination, with a guide, a butt-removing device arranged near said guide, and means for moving an ear of corn along said guide, of a holding device comprising two coöoperating members arranged to engage said ear of corn and hold the same in engagement with said guide.
24. In a machine of the character described, the combination, with a guide, and a butt-removing device arranged near said guide, of a holding device comprising two coöoperating members arranged to engage the opposite sides of an ear of corn and hold the same in engagement with said guide, and feeding means arranged to pass between said coöoperating members and move said ear of corn along said guide.
25. In a machine of the character described, the combination, with a guide, a butt-removing device arranged near said guide, and means for moving an ear of corn along said guide, of a support, and means arranged above said support and coöperating therewith to hold said ear of corn in engagement with said guide.
26. In a machine of the character described, the combination, with a guide, and a butt-removing device arranged near said guide, of a supporting member, and a roller arranged above said supporting member and coöperating therewith to hold an ear of corn in engagement with said guide.
27. In a machine of the character described, the combination, with a butt-removing device a guide, a support for an ear of corn, and positive means for moving an ear of corn along said guide and into engagement with said butt-removing device, of positively actuated means arranged above said support and coöperating therewith to hold said ear of corn against said guide while it is being moved along said support.
28. In a machine of the character described, the combination, with a butt-removing device, a support for an ear of corn, and means for feeding said ear of corn along said support, of a guide comprising two substantially parallel members spaced apart to receive the butt-end of said ear between them, and means for positively holding said ear of corn in engagement with said guide.
- In testimony whereof we affix our signatures in the presence of two witnesses.
